HEAT TREATING FURNACE

Henry H. Harris, Champaign, Ill.

Application October 12, 1937, Serial No. 168,546

4 Claims. (Cl. 263—6)

My invention relates generally to furnaces used in the heat treatment of metals, and specifically relates to the means for conveying heat to the work being treated therein. My invention is concerned with that type of furnace in which the work being treated is travelled through the furnace on roller rails or skids, or else disposed on trays, boxes, or other containers, for travel through the furnace.

Most heat treating furnaces are heated by tubes which are secured to the side walls of the furnace, extending either vertically or longitudinally thereof. These tubes are heated by burners the mouths of which extend into the ends of the tubes, and in turn these tubes impart heat, as by radiation and convection, to the furnace interior and hence the furnace charge. The tubes are removed from the roller rails or skids over which the charge is travelled, and I have found that this method of heating the furnace and the work therein consumes a great amount of time and fuel, prolongs the process, and is thus rather unsatisfactory. The main object of my invention is to provide means for reducing the time and fuel necessary to heat the charge or work being treated within the furnace, and performing the heat treating operation more quickly and efficiently.

Another object of my invention consists in the provision of a heat-treating furnace wherein the heating means are in close proximity to the work being treated.

A further object of my invention consists in the provision of a heat treating furnace wherein hollow tubes are employed as work supporting means as well as heating means.

Broadly, I accomplish these objects, and related objects, by replacing the skids or roller rails, over which the furnace charge is conventionally travelled, by hollow tubes, and then provide for the heating of said hollow tubes.

In the drawing annexed hereto and made a part hereof,

Figure 1 is a vertical section through a heat treating furnace showing one form of my invention in place therein;

Fig. 2 is a longitudinal section through a portion of the furnace shown in Figure 1 along the line 2—2 thereof, showing the furnace floor in plan;

Fig. 3 is a section along the line 3—3 of Fig. 2; and

Fig. 4 is a view, similar to Fig. 2, of a modified form of my invention.

Referring to the drawing, reference numeral 10

indicates the furnace generally, which comprises floor 12, side walls 14, 14, and roof 16.

In the modification illustrated in Figures 1 to 3 inclusive, a plurality of hollow tubes 18 are disposed crosswise or transversely through the furnace 10, said tubes being secured to furnace floor 12. Each tube 18 has the nozzle of a burner 20 projecting thereinto for heating the interior thereof. In the form shown, alternate burners 20 extend into opposite ends of tubes 18. Tubes 18 may be substantially rectangular, as illustrated, or round, either form being satisfactory. Tubes 18 are larger in diameter and thickness than the conventional tubes used for heating, since in my invention the tubes serve two functions: one, to convey heat—either directly or by radiation—to the furnace charge, and two, to support the weight of the charge during travel through the furnace.

On the top of each tube 18, preferably at the center and at opposite ends thereof, I provide rail means for work support and travel. In the form shown in Figures 1 to 3 inclusive, I mount a roller rail section 22, carrying a total of three rollers mounted on each tube; the roller rail sections being secured at right angles to the tube and extending longitudinally or lengthwise of the furnace and forming a track on which the work is travelled through the furnace. The sections 22 illustrated are short, being of a length substantially equal to the width of tube 18. It is obvious that roller rail sections of length to extend over two, three or even more tubes may be used, and, also that if desired, ordinary skid rails may be utilized to support the work on the tubes during travel through the furnace. For purposes of convenience, I will include both roller rails and skid rails within the term "rails" as same is employed in the appended claims.

Referring to the modified form of my invention illustrated in Fig. 4, hollow rectangular tubes 28 are disposed and arranged on floor 12 of furnace 10 extending longitudinally thereof. In this modification, roller rail sections 32 are shown disposed on top of tubes 28, longitudinally aligned therewith and extending lengthwise of the furnace. Rail sections 32 may be continuous, instead of short lengths as in the form of the invention illustrated in Figures 1 to 3. Rollers may be dispensed with, if desired, and the work travelled through the furnace directly upon the tubes 28, or upon skid rails or saddles supported upon the tubes themselves.

My invention is advantageous in that it brings the heat closer to the furnace charge. The heat-

ed tubes not only make direct contact with the work being treated passing thereover, but also radiate heat to the work, and the work being in such close proximity to the heat source, the time needed to bring the work to the desired heat is materially reduced. A shorter period of time is needed to complete the heat treatment and this, with the saving in fuel, makes the heat treating operation very economical as practised with my invention.

Having described my invention, what I claim and desire to secure by Letters Patent is:

1. In a heat treating furnace comprising a floor, a pair of side walls and a roof, means to convey heat to the interior of said furnace comprising a plurality of tubes disposed within the furnace and on the furnace floor, and means to support work within the furnace during travel therethrough, the work supporting means being disposed and secured directly on upper surfaces of the heat conveying means.

2. In a heat treating furnace comprising a floor, a pair of side walls and a roof, means to support work within said furnace during travel therethrough, and means within said furnace to convey heat to said work, said heating means comprising a plurality of hollow tubes disposed within said furnace and on the floor thereof, and said work supporting means comprising rails disposed and secured on the top of said tubes.

3. A heat treating furnace as in claim 2 in which the hollow tubes are disposed transversely of the furnace and the rails are secured thereon at right angles thereto.

4. A heat treating furnace as in claim 2 in which the hollow tubes are disposed lengthwise of the furnace, and the rails are secured thereon in longitudinal alignment therewith.

HENRY H. HARRIS. 20
